CLAIM

The ornamental design for a protective athletic glove, substantially as shown and described.

DESCRIPTION

FIG. 1 is a front perspective view of the present invention showing my new design;

FIG. 2 is a back perspective view thereof;

FIG. 3 is a front elevation view thereof;

FIG. 4 is a left side elevation view thereof;

FIG. 5 is a bottom view thereof;

FIG. 6 is a back elevation view thereof;

FIG. 7 is a right side elevation view thereof; and,

FIG. 8 is a top view of thereof.

The broken line showing of portions of a wrist is for illustrative purposes only and forms no part of the claimed design.
